UNITED STATES PATENT OFFICE.

GEORGE S. EVANS, OF LENOIR CITY, TENNESSEE, ASSIGNOR TO AMERICAN BRAKE SHOE & FOUNDRY COMPANY, OF MAHWAH, NEW JERSEY, A CORPORATION OF NEW JERSEY.

METALLIC BACK FOR BRAKE-SHOES.

1,109,122.

Specification of Letters Patent. Patented Sept. 1, 1914.

Application filed May 6, 1913. Serial No. 765,894.

To all whom it may concern:

Be it known that I, GEORGE S. EVANS, a citizen of the United States, residing at Lenoir City, in the county of Loudon and State of Tennessee, have invented new and useful Improvements in Metallic Backs for Brake-Shoes, of which the following is a specification.

This invention relates to improvements in metallic backs or backing for brake shoes and has particular application to a back of this type adapted to be embedded in the shoe in the casting of the latter.

In carrying out the present invention, it is my purpose to provide a metallic back for brake shoes which will be constructed in such manner as to possess the maximum strength and wearing qualities and which will embrace the desired features of simplicity, efficiency and durability, the back being preferably formed from a single sheet of metal stamped out and bent into the desired formation.

With the above and other objects in view, the invention consists in the construction, combination and arrangement of parts hereinafter set forth in and falling within the scope of the claim.

In the accompanying drawings; Figure 1 is a view in side elevation of a back for brake shoes constructed in accordance with the present invention. Fig. 2 is a plan view thereof, and Fig. 3 is a cross sectional view through the back.

Referring now to the accompanying drawings in detail, the numerals 1, 1 designate a pair of arms arranged side by side and having the opposite end portions thereof di-

verging outwardly of each other as at 2, while the central part of each arm for the major portion of its length is corrugated as at 3.

The numeral 4 designates a loop disposed at the central portions of the arms and formed integral with the outer edges thereof. Owing to the arms being corrugated the back possesses the maximum strength and when embedded in the shoe supports the latter evenly and uniformly, the diverging ends of the arms forming relatively wide anchoring surfaces to facilitate in the equal distribution of the weight of the shoe.

While I have herein shown and described one preferred form of my invention by way of illustration, I desire to have it understood that I do not limit or confine myself to the precise details of construction herein described and delineated, as modification and variation may be made within the scope of the claim without departing from the spirit of the invention.

I claim:

A metallic backing for brake shoes comprising a pair of arms curved longitudinally and arranged side by side and having the central portions thereof corrugated longitudinally and the opposite end portions flat, and a loop connecting said arms at the central portions thereof and integral with the outer edges of said arms.

In testimony whereof I affix my signature in presence of two witnesses.

GEORGE S. EVANS.
